TRANSFORMER

John M. Wilson, Minneapolis, Minn., assignor to
 Minneapolis-Honeywell Regulator Company,
 Minneapolis, Minn., a corporation of Delaware

Application May 15, 1942, Serial No. 443,101

14 Claims. (Cl. 175—361)

1

This invention relates to transformers but more particularly to improvements therein providing increased economies in the construction of parts, facilitating the ease of assembly of the parts, and generally providing greater utility in transformers not heretofore known in the art.

A broad object of this invention is to provide a transformer of extremely simple construction of which various parts may readily be interchanged or altered whereby the same transformer may be utilized for a multiplicity of transformer purposes.

An important object of this invention is to provide a simple core and winding assembly, an expeditious method of assembling the same, and a novel clamping means for holding the parts in assembled relation.

Another object of this invention is to provide a novel anchor plate for the winding lead wires whereby the electrical connections between the lead wires and the winding are relieved of stresses and strains exerted upon the lead wires.

A further object is to provide a housing for the core and winding assembly of this invention having means formed therein for retaining the assembly in a predetermined position in the housing, and having parts which may be simply altered and/or readily interchanged whereby the transformer may be utilized for various transformer mountings and circuit connections.

A still further object of this invention is to provide a combination transformer and outlet box in which the casing of the transformer is formed in such a manner as to provide an outlet box at each end of the transformer.

Still other objects are those inherent in or implied from the novel construction, combination, and arrangement of parts not specifically recited herein above which will become manifest upon reading the following specification, reference being had to the attached drawings in which

Figure 1 is a face view of one of the core laminations used in the transformer of this invention.

Figure 2 is a perspective view of the core, winding, and clamping means of the transformer illustrating the manner in which the same are assembled.

Figure 3 is a cross-sectional view of the transformer shown in Figure 5, being viewed along the lines 3—3 of Fig. 5.

Figure 4 is another cross-sectional view of the transformer shown in Figure 5, being viewed along the lines 4—4 of Figure 5.

Figure 5 is an elevational view of one assem-

bled form which the transformer of this invention might take, portions of the casing being broken away to better illustrate the construction.

Figure 6 is an elevational view of a second assembled form which the transformer might take, portions of the casing being broken away for the sake of clarity.

Figure 7 is a right side elevational view of the transformer shown in Figure 6.

Figure 8 is an elevational view of a third assembled form which the transformer might take, again portions of the casing being broken away to illustrate the construction and assembly.

Figure 9 is a right side elevational view of the transformer shown in Figure 8.

Figure 10 is a reduced size face view of one combined cover and mounting plate which may be used on the transformer of this invention.

Figure 11 is a reduced size face view of an alternate combined cover and mounting plate which may be used on the transformer of this invention.

Figure 12 is a face view of a development of the transformer casing shown in Figures 3 through 9, 13 and 14.

Figure 13 is an elevational view of a fourth alternate assembled form which the transformer of this invention might take, portions of the casing being broken away to better disclose the particular construction and assembly.

Figure 14 is a right side elevational view of the transformer shown in Figure 13.

Figure 15 is an elevational view of a combined transformer and outlet box which embodies several of the features of this invention, portions of the casing being broken away to illustrate the construction.

Figure 16 is a left side elevational view of the transformer shown in Figure 15.

Referring first to Figures 3, 4 and 5, the numeral 19 generally designates a transformer which comprises a core and winding assembly generally indicated by the numeral 20 and a housing therefor, generally designated by the numeral 21.

The core and winding assembly comprises a primary and secondary winding 22 and 23 respectively, carried by a winding leg 24 of a laminated window type core. The stacked laminations of the leg 24 are pressed into the stacked laminations of the yoke portion 25 of the core, the laminations being held in stacked relation and in pressed relation with respect to each other by a U-shaped clamp, generally designated by the numeral 26.

The clamp 26 comprises a bight portion 27 and legs 28 and 29. The legs 28 and 29 have bent-over portions 30 and 31 which extend parallel to the bight portion 27 and engage the core portions 24 and 25. As will hereinafter be pointed out, the leg portions 30 and 31 are bent over at a time when the laminations are held under pressure. Consequently, the tendency of the laminations to separate provides a frictional means for maintaining the clamp 26 in place on the core.

In Figure 1, a core lamination is shown in which the leg portion 24 is formed integrally with the yoke portion 25. As a matter of fact, the yoke and leg lamination portions are blanked out of the same sheet lamination, the two being separated along the dotted lines 32 and 33. Apertures 34 and 35 are also punched out of the sheet lamination at the lines 32 and 33 for purposes of providing alignment of the lamination portions in the assembly of the core. It will be noted that the bight portion 27 of the clamp 26 is shaped generally similar to the laminations of the yoke 25 having apertures 36 and 37 which coincide with the apertures 34 and 35 of the laminations. The leg portions 30 and 31 are provided with indentations 38 and 39 which also coincide with the apertures 34 and 35 for a purpose hereinafter to appear.

In making a core and winding assembly 20, a plurality of core laminations 24 and 25 are first blanked out. The laminations comprising the yoke 25 are then stacked in the clamp 26 which is preformed to the angular configuration as shown in Figure 2, the leg portions 30 and 31 being bent slightly inwardly. With the apertures 34, 35 of the core laminations in alignment with the apertures 36, 37 of the clamp, the clamp and yoke laminations are assembled on a jig 40, guide pins 41 and 42 carried thereon, occupying the apertures 34, 35 and 36, 37. The leg laminations 24 are next stacked and the windings 23, 22 mounted thereon in any convenient manner. The windings and core leg assembly is then mounted on the guide pins 41, 42 and brought into engagement with the yoke 25. A suitable pressure applying means (not shown) is then applied to the leg 24 forcing the laminations thereof into engagement with the laminations of the yoke 25. The arrangement of the pressure applying means is such that when the leg 24 and yoke 25 are completely engaged, pressure is applied to the laminations of both core portions, and while the pressure is being applied, the leg portions 30 and 31 of the clamp 26 are bent over by any suitable means until the clamp takes the form as seen in Figure 5. The indentation 38 and 39 permit the leg portions 30 and 31 to clear the guide pins 41 and 42. The assembly 20 is then conveniently removed from the jig 40 by simply sliding the assembly off of the guide pins 41 and 42.

The ends 43, 44 of the windings 22, 23 respectively, are brought out to terminal boards 45 and 46 which may be identical, and may be formed of any suitable insulating material. Each board 45, 46 is inserted between one end of the windings and the yoke 25, each being bifurcated to straddle the leg 24 with the bifurcations 47 and 48 fitting snugly between the leg 24 and the yoke 25 as clearly seen in Figure 4. The ends of the windings are wound with one or more turns about projections 49 on the boards 45, 46 and soldered to suitable lead wires 50 and 51 for the windings 22 and 23 respectively. The lead wires 50 and 51 are securely anchored to the boards

45 and 46 by being wound in a series of half turns in apertures 52 formed in each board 45, 46. Thus, by reason of the snug fit between the boards 45, 46 and assembly 21, stresses and strains exerted on the lead wires 50, 51 in making circuit connections and in the general handling of the transformer 20 are transmitted to the assembly 21 thereby relieving the soldered connections between the windings and lead wires of such stresses and strains.

The housing 21 comprises a box-shaped casing 53 and a cover 54 therefor. Referring to Figure 12, it will be seen that the casing 53 is formed of a single cross-shaped sheet of metal, the center portion 55 of which corresponds to the top of the casing and the arms 56, 57, 58 and 59 of which comprise the sides of the casing, the sides being bent down about the dotted lines 60, 61, 62 and 63 to form the box shape thereof.

The assembly 20 is retained in the casing 53 in a definite position therein by depressions 65 formed in the sides 56 and 57 which engage the sides of the core yoke 25 as best seen in Figures 3 and 4. It is to be noted that the casing 53 is formed in such a manner that the sides 55, 56 and 57 engage the core. Consequently, the assembly 20 can be removed from the casing only by sliding the same between the depressions 65. It is to be further noted that the clamp 26 is somewhat narrower than the width of the yoke 25 to permit the depressions 65 to engage the yoke. It is obvious that if the depressions were extended adjacent the clamp 26, it would be impossible to remove the assembly 20 from the casing because of the noncontinuity of the clamp on one side of the core. It is further obvious that if the assembly 21 were rotated through 90° in the plane of the depressions 65, as seen in Figure 3, the depressions 65 would extend adjacent the relatively rounded edges 66 of the clamp 26 and thereby necessitate the use of much deeper depressions to securely retain the assembly 20 in the casing 53.

The cover 54 for the housing 21 is shaped similarly to a standard outlet box cover, and is secured to the casing 53 by conventional tongue and slot connections. The sides 56, 57, 58 and 59 carry tongues 67, which engage slots 69 formed in the cover 54. The cover 54 is further provided with a number of apertures 70, by means of which the transformers may be mounted to an outlet box. A further aperture 71 is provided through which the lead wires 51 may be drawn so that the primary winding 22 may be connected into the line circuits brought into the outlet box. It is to be noted that the sides of the casing 53 are substantially the same height as the assembly 20. Consequently, when the cover 54 is secured to the casing 53 the assembly 20 is secured against any movement in the housing 21.

A plate 73 is disposed adjacent the side 59 of the casing 53 and has an internally threaded nipple 74 staked thereto through which the secondary lead wires 51 are drawn for connections to external circuits. The side 59 is provided with an indentation 75 to accommodate the nipple 74. The plate 73 is retained against the side 59 by depressions 76 similar to the depressions 65 which are also formed in the casing sides 56 and 57. Thus, by this arrangement the secondary winding 23 may be connected to a circuit brought through standard conduit since the nipple 74 can be connected to the conduit. A screw 77 is used to metallically connect the plate 73 to the casing side 59 to satisfy underwriters' requirements with

respect to providing a continuous ground for the circuit.

Usually, the primary and secondary windings are connected to their respective circuits when the transformer 19 is completely assembled. However, it is obvious that because of the simple means by which the cover 54 is secured to the casing 53 and the simple means by which the assembly 20 and plate 73 are retained in the casing 53, that the connections to the windings may conveniently be made while the plate 73 and assembly 20 are removed from the casing, thus facilitating the ease of attachment of the plate 73 to the conduit.

In Figures 6, 7, 8, 9, 13 and 14 transformers are shown which are generally similar to the transformer 19 of Figure 5. Accordingly, wherever possible, similar reference characters will be used to indicate similar parts.

Referring to Figures 6 and 7, the numeral 78 generally designates a transformer which is the same as transformer 19 except that a panel 79, formed of any suitable insulation material, has been substituted for the plate 73 and the ends 44 of the secondary winding 23 are connected to terminals 80 provided on the panel 79. The terminal board 45 is omitted and inserted in place thereof is a wedge 81 to assure a frictional fit of the primary terminal board 45 between the windings and the core as before. When desirable, a fuse 82 may be inserted in series with the secondary winding as clearly seen in Figures 6 and 7.

In Figures 8 and 9 a transformer 83 is shown which differs from the transformer 19 in that an externally threaded nipple 84 is staked to the casing side 58 which may be provided with an aperture as indicated by the dotted lines 85 in Figure 12. The transformer 83 may be mounted on an outlet box by mounting an outlet box cover plate 86, generally similar to the outlet box cover plate 52 of Figure 5, on the nipple 84, the same being secured thereto by a nut 87. The cover plate 86 is prevented from rotating relative to the casing 53 by a tongue and slot arrangement between the sides 56 and 57 of the casing 53 and the cover plate 86, the sides 56 and 57 having tongues 88 which enter slots in the cover plate 86 similar to the slots 69 of cover plate 52.

It may be desirable to mount the transformer 83 on a wall or other suitable support rather than on an outlet box. For this purpose, the transformer 83 is provided with a mounting bracket 89 which has slots 90 similar to the slots 69 of the cover plate 54 by means of which it is secured to the casing 53 as in the case of the cover plate 54. The bracket 89 is also provided with additional apertures 91 by means of which the transformer may conveniently be mounted on a wall or other support. When the mounting bracket 89 is used, both windings of the transformer 83 are connected into circuits which are brought through conduit. Accordingly, it is obvious that since the necessary connections between the conduit and the transformer may be made when the assembly 21 and the plate 73 are removed from the casing 53, such connections are greatly facilitated by such removal.

In Figures 13 and 14 a transformer 92 is shown which combines the features of the transformers 78 and 83. Transformer 92 may be used with or without the outlet box cover plate 86, the primary lead wires 50 either being connected to circuits in the outlet box or to circuits carried through conduit connected with the nipple 84. The transformer 92 is further provided with the panel 79

of transformer 78. In the transformer 92 however, the fuse 82 has been eliminated to illustrate the construction when a fuse is not used.

In Figures 15 and 16 a combined outlet box and transformer 93 is shown in which the core and winding assembly 20 is used and similarly retained in a housing therefore as in the case of the foregoing transformers. The housing comprises a casing 94 which is formed of a single sheet of metal folded to provide three sides of the casing 95, 96 and 97 and a cover 98 for the casing which is shaped and fastened similarly to the mounting bracket 89 described in connection with transformers 83 and 92, conventional tongue and slot means generally indicated at 99 being used. The sides 96 and 97 carry depressions 100 which determine the position of the assembly 20 in the casing 94 as in the case of the foregoing transformers.

The remaining casing sides for enclosing the assembly 20 comprise plates 101 which are disposed in the housing midway between the assembly and the ends of the casing and cover 98. The spaces between the ends of the plates 101 and the ends of the housing comprise outlet box compartments. The plates 101 are retained in a definite position in the housing by depressions 102 formed in the casing sides 96 and 97 and arranged on each side of the plates 101 as clearly seen in Figures 15 and 16. Apertures 103 are provided in the plates 101 through which the lead wires 50 and 51 of the primary and secondary windings 22 and 23, respectively, are drawn for connection with their respective circuits which may be drawn into the outlet box compartments through anyone of a number of apertures 104 formed upon removal of the knock-out plugs 105 provided in the casing sides 95, 96 and 97. The casing side 95 and the cover 98 are provided with bent portions 106 and 107 respectively, to which cover plates 108 for the outlet boxes may be secured, suitable attaching screws 109 being used for this purpose.

From the foregoing, it is now apparent that I have provided transformers which are extremely simple in construction and well adaptable for a multiplicity of transformer mountings and circuit connections. The wide utility of these transformers is made possible, largely, by virtue of the novel means for retaining the core and winding assembly in the housing therefor, since by this arrangement, other sides of the housing are available to accommodate various circuit connections and to accommodate various interchangeability of parts to make such circuit connection variations possible. It has also been seen how the construction of the casing has made alternative mountings for the transformers possible.

While I have disclosed several preferred embodiments of my invention, it is to be understood that the disclosures were for purposes of illustration only and not to be considered in a limiting sense, as I contemplate all such further embodiments and changes thereof which would naturally occur to those skilled in the art, without departing from the spirit of the invention as defined by the appended claims.

I claim as my invention:

1. In a transformer, spaced integrally connected yokes comprising a plurality of stacked laminations, a winding leg comprising a plurality of stacked laminations and a winding surrounding the same and holding said laminations together, said yokes and winding leg being so

shaped that the winding leg may be pressed into said yokes for holding said parts together, and clamping means comprising a substantially U-shaped member including bent over portions pressing laminations of said yokes together and holding the same in pressed relation whereby the tendency of said yoke laminations to separate firmly holds said clamping means in place.

2. In combination, an electrical device having a winding, an anchoring device secured to said electrical device and provided with a plurality of apertures, an end of said winding being secured to said anchoring device, and a lead wire electrically connected to said end of said winding and threaded through said apertures in a series of half turns whereby said lead wire is anchored to said device thereby relieving said electrical connections of stresses and strains exerted upon said lead wire.

3. In combination, an electrical device having a winding, a combined terminal and anchor board secured to said device, a lead wire for connection to an end of said winding, means for electrically connecting said lead wire to the end of said winding on said board, and a plurality of apertures formed in said board for receiving said lead wire in a series of half turns whereby said lead wire is anchored to said device thereby relieving said electrical connections of stresses and strains exerted upon said lead wire.

4. A transformer comprising a laminated core including a plurality of interfitting sections, a winding on one of said sections, clamping means comprising a substantially U-shaped member for holding said sections in assembled relation, a casing for said core and winding, said casing being formed of sheet stock in such a manner that three sides thereof engage said core, and means comprising extrusions formed in two of said three sides for engaging and retaining said core in said casing in a predetermined position therein, and said clamping means being formed in such a manner as to permit an insertion of said core into said casing between said retaining means.

5. A transformer comprising a core including a plurality of interfitting sections, a winding on one of said sections, clamping means for holding said sections in assembled relation, lead wires connected to said winding, an anchor plate for said lead wires inserted between said winding and core, said clamping means being formed in such a manner as to permit said anchor plate to be inserted between said winding and core, a housing for enclosing said core and winding, means formed in said housing engageable with said core for retaining the same in the housing in a predetermined position therein, said clamping means being formed in such a manner as to permit an insertion of said core into said housing between said retaining means, and aperture means provided in said housing through which said lead wires may be drawn.

6. A transformer comprising a winding and core assembly, a housing for the assembly, means formed in the housing for retaining the assembly in the housing in a predetermined position therein, a member removably associated with the housing and disposed adjacent a first side thereof, means formed in a second and third side for retaining said member adjacent said first side, electrical conductor means for connecting the winding to an external circuit, and said first side and said member being formed in such a manner

as to accommodate said electrical conductor means.

7. A transformer comprising a winding and core assembly, a housing for the assembly, means formed in the housing for retaining the assembly in the housing in a predetermined position therein, a member removably associated with the housing and disposed adjacent a first side thereof, means formed in a second and third side for retaining said member adjacent said first side, said member being insertable into said housing between said first side and the retaining means formed in said second and third sides, lead wires for the winding, and standard coupling means for connection to standard conduit, secured to said member through which said lead wires may be drawn, said first side being formed in such a manner as to accommodate said coupling means.

8. A transformer comprising a core and winding assembly, a panel, terminals on the panel for connections with the winding, a housing for the assembly and panel, said panel being disposed adjacent one side of the housing, means formed in second and third sides of the housing for retaining the assembly and panel therein, said assembly and panel being insertable into and removable from the housing by sliding the same between said retaining means whereby the windings may be secured to the terminals and the assembly and panel inserted into the housing as a unit, and said first side being formed in such a manner whereby external connections may be made with said terminals when the transformer is in an assembled condition.

9. A transformer comprising a plurality of windings, a core for said windings, a housing for enclosing said windings and core, means for retaining said windings and core in said housing, electrical conductor means for connecting said windings with external circuits, said housing comprising a first pair of sides each of which is formed in such a manner as to accommodate the conductor means for one of said windings, one of said first pair of sides being an outlet box cover and having an aperture therein through which the conductor means for one of said windings may be drawn, the other of said first pair of sides comprising a member associated with said housing, and means formed in a second pair of sides for engaging said member and retaining the same in said housing in a predetermined manner whereby said member may be inserted or removed from said housing by sliding the same between said formed means and said housing.

10. A transformer comprising a plurality of windings, a core for said windings, a housing for enclosing said windings and core, means for retaining said windings and core in said housing, electrical conductor means for connecting said windings with external circuits, said housing comprising a first pair of sides each of which is formed in such a manner as to accommodate the conductor means for one of said windings, one of said first pair of sides having a standard threaded nipple secured thereto, through which the conductor means of one of said windings may be drawn, an outlet box cover secured to the nipple by means of which the transformer may be mounted on a standard outlet box, said housing comprising a third side which serves as a mounting bracket by means of which the transformer may be mounted on a suitable support, said housing comprising fourth and fifth sides in engagement with said outlet box cover and said third side, and means carried by said fourth and

fifth sides for preventing rotation between said outlet box cover and said housing.

11. A transformer comprising a plurality of windings, a core for said windings, a housing for enclosing said windings and core, means for retaining said windings and core in said housing, electrical conductor means for connecting said windings with external circuits, said housing comprising a first pair of sides each of which is formed in such a manner as to accommodate the conductor means for one of said windings, one of said first pair of sides having a standard threaded nipple secured thereto through which the conductor means of one of said windings may be drawn and by means of which the transformer may be secured to standard conduit and outlet boxes, the other of said first pair of sides comprising a member removably associated with said housing, said member having a standard nipple secured thereto through which the conductor means for another of said windings may be drawn and by means of which the transformer may be connected to standard conduit, and means formed in said housing for retaining said member in a predetermined position therein.

12. In combination, including a casing, a transformer spaced in the casing, the transformer consisting of spaced integrally connected yokes comprising a plurality of laminations and an interfitting leg portion comprising a plurality of laminations having windings for holding the laminations together, and a U-shaped clamping member including bent over portions for holding the leg and its windings in operable relation to said yokes.

13. In combination, including a casing, a transformer spaced in the casing, the transformer consisting of spaced integrally connected yokes comprising a plurality of laminations, aperture means in each of the yokes, an interfitting leg portion comprising a plurality of laminations having windings for holding the laminations together, aperture means in at least two sides of the leg portion, a U-shaped clamping member having bent over portions with apertures therein for holding the leg and its windings in operable relation to said yokes, and when the clamping member is in holding relation to said transformer the apertures of the clamping member are aligned with the apertures in the yokes and the leg portions of the transformer.

14. A transformer comprising windings and a core assembly, clamping means for holding the winding and core assembly in assembled relation, electrical conductor means connected with one of the windings, means for anchoring the conductor means associated with the one winding, a housing for the assembly, one side of the housing having outlet means for the conductor means, a member removably associated with the housing, means on second and third sides of the housing for retaining the windings and core assembly in a predetermined position in said housing, means on the said second and third sides of the housing for positioning the removable member adjacent a fourth side of the housing, and means associated with the removable member so that conductor means may be electrically connected with the ends of the other of said windings.

JOHN M. WILSON.
